UNITED STATES PATENT OFFICE.

POMEROY H. FORBES, CHARLES C. FRENCH, AND ARTHUR LEE, OF TOPEKA,
KANSAS.

MECHANISM FOR MAKING, BREAKING, AND SWITCHING ELECTRIC CIRCUITS FOR RAILWAY-SIGNALS.

SPECIFICATION forming part of Letters Patent No. 594,614, dated November 30, 1897.

Application filed March 26, 1897. Serial No. 629,378. (No model.)

To all whom it may concern:

Be it known that we, POMEROY H. FORBES, CHARLES C. FRENCH, and ARTHUR LEE, citizens of the United States, residing at Topeka, in the county of Shawnee and State of Kansas, have invented certain new and useful Improvements in Mechanism for Making, Breaking, and Switching Electrical Circuits for Railway-Signals; and we do hereby declare the following to be a full, clear, and exact description of the invention, such as will enable others skilled in the art to which it appertains to make and use the same.

Our invention has relation to improvements in means or mechanism for making and breaking electrical circuits for railway-signals; and the object is to provide improved means of the kind named and for the purposes intended which is simple in construction and certain and effective in operation.

The hereinafter-described mechanism is designed to be operated by the wheels of a car passing over the rails and contacting an actuating-bar disposed adjacent to the track-rail, and it is intended to produce a device or apparatus which may be applied in all instances where a railway-signal is operated by electrically-controlled means, including a closed wire circuit opened by the agency of a passing car and closed by the operation of the interposed mechanism.

We have fully and clearly illustrated the invention in the accompanying drawings, wherein—

Figure 1 is a side view of the device, where in the depressible bar or lever is in raised or normal position, the cylinders being broken away to show the piston-valves. Fig. 2 is a plan view of the complete mechanism, the cover of the casing or box being removed. Fig. 3 is a side view of the depressible bar or lever in its normal position, showing it arranged in relation to the track-rail and a car-wheel about to move thereon. Fig. 4 is a side elevation showing the bar or lever depressed by a car-wheel which has passed nearly over the length of the bar and as moving in the direction of the arrow. Fig. 5 is an end view in elevation, the closure or end of the casing being removed to display the mechanism.

A designates a rail of a section or block of railway, adjacent or contiguous to which is disposed and secured a suitable casing B, consisting of a box of proper material adapted to receive and hold the mechanism, and being made deeper on one side, as at d, to hold the air-cylinders, and having a side extension not so deep as the other part, as indicated at d' in the drawings. A suitable cover (not shown) is provided to lie over the box and protect the inclosed mechanism from the elements and against unwarranted intrusion.

C C' designate rock-shafts journaled in the respective side pieces of the box adjacent to, the ends thereof, as at 1, which shafts have 65 their ends projecting through one side of the box, as at 1', and on these projecting portions, designed to stand contiguous to the track-rail and in alinement therewith, are mounted crank-arms 2 2', arranged with their 70 upper ends somewhat elevated at an incline and inward and toward each other, as shown in the drawings, and to the inner ends of the arms 2 2' are pivotally connected and supported the respective ends of a bar or lever 75 D, which constitutes the element or medium by which the rock-shafts and the associated mechanism are actuated. The upper or contact surface of the bar D is made in a double incline, the inclines ascending from each end 80 to the middle of the bar, as shown in the drawings at 4 4'. The bar D is so disposed with its tread-face in relation to the tread of the rail as to stand with the initial points of contact flush with the tread of the rail, so 85 that when a moving car contacts with the bar from either direction the respective rock-shafts will be rocked, but not both, since from the construction and arrangement of the supports of the bar it will be perceived that the 90 stroke from either direction will tend to throw the bar in the direction of the force, as indicated in Fig. 4 of the drawings, which shows the position the bar assumes when first struck and depressed, and which it maintains during 95 the passage of the wheel.

At suitable points on the rock-shafts C C' are secured short arms 5 5', the lower ends of which are secured to rods 6 6', sliding in guides or ways in supports 7 7', suitably 100

mounted and secured in the box, substantially as shown in Figs. 1 and 2 of the drawings. The stems of the rods 6 6' are screw-threaded, as at 8, and are provided with adjusting-nuts 9 9', which may be adjusted and set on the threaded stems to lodge against the guide-supports 7 7' and limit and control the extent of the throw of the arms 5 5' on the rock-shafts and for the purpose of adjusting the bar D to the proper height with relation to the face of the track-rail. To the inner ends of the rods 6 6' may be connected turnbuckles 10 10', carrying between them a retractile spring 11, by which the mechanism is returned to the normal position when the actuating lever or bar is released from the action of the depressing medium or car-wheel. The turnbuckles may be used to alter the tension of the spring as may be necessary or desirable. On each rock-shaft is rigidly fixed a lug or finger 12, in the free end of which is fitted a contact screw 12', which moves in the path of a contact-spring 13 and stands normally in contact therewith.

To retard the return action of the contact mechanism, we provide the following-described means: In the deeper portion or compartment of the box are arranged two horizontally-disposed air-cylinders 15 15', their inner and approaching heads being formed with bearing-lugs 16, which are pivotally mounted on a shaft 17, secured across the box, the support being thus so as to allow the outer ends of the cylinders to move up and down a short distance to compensate for the variation in the movement of the piston-rods and permit the piston to pull in line with the line of motion or force. In each of these cylinders is fixed a piston 18, having its head provided with valves *v*, arranged in such a manner as to let air in freely when the piston is withdrawn, but which prevent the escape of the air when the piston moves in the opposite direction. Any suitable valve may be used to effect the purpose, and to provide additional means for this purpose the valves may be increased in number to suit. In the inner head of each piston-cylinder is fitted a small petvalve *v'*, which can be adjusted so as to permit the return movement of the piston to be rapid or slow, as may be desired. The piston-rod of each piston is connected to an arm on the rock-shafts, so that when the shaft is rocked the piston will be withdrawn by the action which rocks the shaft. The object of these air-cylinders and their pistons is to prevent the depressible and actuating-bar from instantly returning to raised normal position and from being violently impacted by every passing wheel of a train. A further object, if desirable, is to prolong the separation of the electrical contact-points. It will be perceived that when the actuating-lever has moved the point of the contact-screw away from the contact-spring and the other parts have been returned to their normal positions the contact will be retarded

by the action of the pistons at all times sufficient to permit the associated signal mechanism to operate the signal.

The operation of the apparatus is as follows: A car moving in the direction of the arrow, as indicated in Fig. 3 of the drawings, passes onto the depressible bar and gradually but quickly depresses it from the time of contact until the middle of the bar is reached, when it has been pushed down to its farthest limit and the tread is substantially in alignment with the face of the rail. As the bar is moved down the rock-shaft is rocked, the rotation carrying away the finger 12 from contact with the spring 13, and consequently opens whatever circuit may have been active through these elements. At the same time the movement of the rock-shaft through the action of the arm 6 extends the spring 11, so that when the actuating-bar is relieved of the pressure upon it the said spring will at once act in the effort to return the rock-shaft and connected parts to their normal positions, but will be retarded and resisted in the movement by the action of the pistons, which consequently retards the return of the electric contact, and thus the circuit will remain broken for a time long enough to permit the signal-operating mechanism to effect its purpose in operating the signal.

The circuits with the interposed batteries and signal mechanism are not shown further than to indicate their connections completing the circuits broken and closed by the mechanism of our device, and by reference to the drawings in Fig. 2 it will be perceived that the circuits are through the contacts 13 and 14 by wires *w w*.

What we claim is—

1. A mechanism for making and breaking an electrical wire signal-circuit, comprising a depressible bar disposed parallel with the track-rail, a suitably-journalized rock-shaft, an arm on the rock-shaft connected to said bar, a finger on the rock-shaft, a contact-spring in the path of the said finger, circuit-wires connected to said contact elements, an arm on the rock-shaft, a threaded rod secured to this arm, an adjusting-nut on the threaded rod, a guide for the rod against which the nut lodges, a retractile spring secured to the threaded rod, and means connected to the rock-shaft to retard the return movement of the depressible bar and separation of the contacts.

2. A mechanism for making and breaking an electrical wire signal-circuit, comprising a suitable box or casing, a depressible lever or bar having a double-incline tread-surface arranged adjacent to the tread of the rail, rock-shafts journalized across the box, arms connecting the rock-shafts to the ends of the depressible bar, depending arms on the rock-shafts, a retractile spring connecting the depending arms to return the rock-shafts to normal positions, fingers on the rock-shafts, contact-springs in the path of said fingers, cir-

cuit-wires connected to said contact elements, air-cylinders in the casing, pistons in the cylinders, and arms connecting the piston-rods to the rock-shafts.

- 5 3. A mechanism for making and breaking an electrical wire signal-circuit, comprising a suitable box or casing, a depressible bar or lever having a double-incline tread-surface arranged adjacent to the tread of the track-rail, rock-shafts journaled across the box, arms connecting the rock-shafts to the ends of the depressible bar, depending arms on the rock-shafts, a retractile spring connecting the depending arms to return the rock-shafts to 10 normal positions, fingers on the rock-shafts, contact-springs in the path of said fingers,

circuit-wires connected to said contact elements, air-cylinders in the casing, regulating-valves in the cylinder-heads to adjust and regulate the exit of air from the cylinders, 20 pistons in the cylinders, valves in the pistons to admit air when the pistons are withdrawn, and piston-rods having their ends connected to arms on the rock-shaft.

In testimony whereof we affix our signatures in presence of two witnesses.
